(57) **CLAIM**

The ornamental design for a display screen with a graphical user interface, as shown and described.

DESCRIPTION

FIG. 1 is a front view of a first image in a sequence for a display screen with a graphical user interface;

FIG. 2 is a front view of a second image in a sequence for a display screen with a graphical user interface;

FIG. 3 is a front view of a third image in a sequence for a display screen with a graphical user interface; and,

FIG. 4 is a front view of a fourth image in a sequence for a display screen with a graphical user interface.

The appearance of the transitional image sequentially transitions between the images shown in FIGS. 1-4, respectively. The process or period in which one image transitions to another image forms no part of the claimed design.

The outermost broken line rectangle in FIGS. 1-4 show the display screen, and form no part of the claimed design. The portions of the transitional graphical user interface shown in broken lines form no part of the claimed design.

1 Claim, 4 Drawing Sheets
